CLAIM

The ornamental design for a hub cap retaining clip, as shown and described.

DESCRIPTION

FIG. 1 is a top perspective view of the new design for a hub cap retaining clip in accordance with the present invention; FIG. 2 is a bottom perspective view of the hub cap retaining clip shown in FIG. 1;

FIG. 3 is a front elevation view of the hub cap retaining clip shown in FIG. 1;

FIG. 4 is a rear elevation view of the hub cap retaining clip shown in FIG. 1;

FIG. 5 is a top plan view of the hub cap retaining clip shown in FIG. 1;

FIG. 6 is a bottom plan view of the hub cap retaining clip shown in FIG. 1;

FIG. 7 is a right side view of the hub cap retaining clip shown in FIG. 1; and,

FIG. 8 is a left side view of the hub cap retaining clip shown in FIG. 1.

The broken lines (dot-dot-dash lines) shown within the various figures of the hub cap retaining clip are provided as shading.

1 Claim, 4 Drawing Sheets
